UNITED STATES PATENT OFFICE

GILBERT ALAN ROBINSON, OF HULL, ENGLAND, ASSIGNOR TO F. ROBINSON AND COMPANY, LIMITED, OF HULL, ENGLAND

TINS, IRON KEGS, AND LIKE METAL CONTAINERS

Application filed January 28, 1930, Serial No. 424,012, and in Great Britain January 31, 1929.

This invention relates to tins, iron kegs and like metal containers of the kind fitted with lids of the lever lid type, the chief object being to provide simple and effective means for 5 securing or holding the lid of the container in position.

According to the invention the upper edge or rim of the container is constructed with a comparatively wide external flange portion, 10 the outer circumference or edge of which lies concentric to and at some distance away from the outer circumference or edge of the lid when the latter is applied, and is characterized in that stampings or lugs are passed 15 through slots or openings in the flange and are adapted to be bent over the edge of the lid to secure it in its closed position. The flange portion of the container which may be beaded will by preference be recessed or formed 20 with an annular groove or depression above which the rolled or beaded edge of the lid will lie, so that the distance between the two edges of the flanges on the container and lid will afford an increased leverage for raising 25 the lid.

In order that the invention may be clearly understood and readily carried into effect, the same will now be more fully described with reference to and by the aid of the accompanying drawing; wherein:—

Figures 1 and 2 are respectively a side elevation and a section of the upper part of the tin, iron keg or like metal container.

Figure 3 is an enlarged view of part of 35 Figure 2, showing one form of lid-securing means.

Figure 4 is a similar view to Figure 3, but illustrating a modified form of the lid-securing means.

Referring to the drawing, the upper edge or rim of the container 1 is constructed with a comparatively wide external flange portion 2, the outer circumference or edge of which lies concentric to and at some distance away 40 from the outer circumference or edge of the lid 3 when the latter is applied. The flange 2 which is formed with a beaded or rolled-over edge 4 is recessed or formed with an annular groove or depression as shown, and the 45 rolled or beaded edge 5 of the lid 3 lies above

said circular groove or depression when applied, so that the distance between the two edges or beadings 4, 5 on the container 1 and lid 3 afford an increased leverage for raising the lid. The securing or holding means for 55 the lid 3, as shown in Figures 1, 2 and 3, comprise stampings or lugs 6, passed through slots or openings 7 in the flange 2 at the upper edge or rim of the container 1, the upper ends of said stampings or lugs 6 being bent 60 over the edge 5 of the lid 3, to secure the latter in its closed position. The stampings or lugs 6 shown in Figures 1, 2 and 3 are of tee-shape so that when applied, the cross-portions of 65 said stampings or lugs 6 lie beneath the flange 65 2, whilst the vertical links of the tees project through the slots or openings 7 so that they can be readily bent over the lid when applied to lock it in position. In lieu of the stampings or lugs 6 being of tee-shape they may, as 70 shown at Figure 4, consist of plain stampings, and the lower portions may be bent around the beaded edge 4 of the container flange 2, to secure said stampings or lugs 6 in position or afford hinged connections therefor. As 75 shown, in Figures 1 and 2, a pair of oppositely disposed stampings or lugs 6 may be furnished with openings to enable the extremities of a bail or like handle 8 to be fitted thereto for carrying the container 1. In this connection the bail or handle securing lugs 6, instead of being passed through the flange 2 from below as shown, may be passed through 80 said flange 2 from above and then bent around the beaded edge 4 to afford connections for 85 the ends of the bail or handle 8.

The aforesaid wide levering flange 2 and the stampings or lugs 6 may be applied to straight sided containers or to containers made with either contracted or expanded neck 90 portions, or tapered containers. Thus, the container 1 may be straight sided as shown in full lines at Figures 1 and 2, or the mouth or open end of the container may be of the type which is corrugated so as to produce a 95 contracted or expanded neck which affords a seating for the flange of the lid, and at the same time allows of the lid being levered off more readily than with the usual type of lidded container. The form of container 1 100

having a corrugation to afford a reduced neck is shown in dotted lines at Figures 1 and 2.

I claim:—

- 5 1. In combination a container open at the top and having adjacent its upper edge a laterally projecting flange through which are formed a plurality of circumferentially spaced apertures, said flange being of con-
- 10 cave shape in radial cross section, a lid the diameter of which is substantially the same as the diameter of the circle in which the circumferentially spaced apertures are located, and fastenings extending through the aper-
- 15 tures in said flange and having their upper ends bent over the adjacent edge of the lid and their other ends directly engaging the flange to prevent bodily upward movement through said apertures.
- 20 2. In combination, a container opened at the top and having an apertured flange extending outwardly adjacent its upper edge, a lid the marginal edge of which is within the margin of said flange when applied to the
- 25 container and fastening members extending upwardly through the apertures, the upper ends of said fastening members being bent laterally into engagement with the lid and the lower portions bent around the edge of
- 30 the flange to secure them in position and form hinged connections therewith.
